(57) **CLAIM**

The ornamental design for a speaker device, as shown and described.

DESCRIPTION

The present application is related to U.S. Design patent application Ser. No. 29/621,001, filed concurrently herewith, the entire disclosure of which is incorporated herein by reference.

FIG. 1 is a top perspective view of a speaker device showing our new design;

FIG. 2 is a bottom perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines in the figures illustrate the portions of the design that form no part of the claimed design.

1 Claim, 6 Drawing Sheets
